UNITED STATES PATENT OFFICE.

MARY KOCIAN, MARY FERRI, JOSEPH KOCIAN, AND CHARLES FERRI, OF JERSEY CITY, NEW JERSEY.

CLOTHESLINE CLEANER.

Application filed October 12, 1922. Serial No. 594,134.

To all whom it may concern:

Be it known that we, MARY KOCIAN, MARY FERRI, JOSEPH KOCIAN, and CHARLES FERRI, citizens of the United States, residing at 5 Jersey City, in the county of Hudson and State of New Jersey, have invented certain new and useful Improvements in Clothesline Cleaners, of which the following is a specification.

10 This invention relates to improvements in devices for cleaning pulley clothes lines. Heretofore it has been found impractical to clean both the upper and lower stretches of such a line, while hung, because of the 15 fact that the knot in the line could not pass about the pulleys over which the line was trained. With the expenditure of considerable energy one could clean the lower stretch of the line but the top stretch could not be 20 cleaned without disengaging the line from the pulleys or unhooking the pulleys, and as this involved considerable labor the line was generally permitted to accumulate dirt and dust upon its upper stretch. Under 25 these conditions, clothes hung upon the line would, in windy weather, be blown in contact with the upper stretch of the line and would become soiled. In consideration of the foregoing it is the primary object of the 30 present invention to provide a device adapted to be applied to any ordinary pulley line and adapted in its operation to thoroughly clean both stretches of the line, or in other words substantially the entire length of the line.

35 Another object of the invention is to provide a device for the purpose stated which may be readily applied to the line even in the darkness and without interference on 40 the part of the knot in the line and which device will embody a cleaning member in the nature of a cloth supported and firmly held in place by gripping means adapted to draw the wiper cloth snugly about the line 45 so as to most effectually wipe the dust and dirt therefrom in the travel of the device between the line supporting pulleys.

Another object of the invention is to so 50 construct the device that the cleaning cloth employed in connection therewith may be adjusted so as to present successive portions of its area to the line thus adapting a clean or fresh portion of the cloth to be brought into position for use before or after opera- 55 tion.

Another object of the invention is to provide a device for the purpose stated embodying a pair of members swingingly connected and arranged to hold between them a cleaning cloth which is snugly and firmly 60 drawn about the stretches of the clothes line by the said members when closed, the members being provided with projecting fingers which when properly engaged by the lower stretch of the clothes line will effect a yieldable closing of the device about the said lower stretch of the line, the fingers serving also as a means whereby slack may be taken up in the line and whereby the device may be connected with the lower stretch of the 70 line for movement therewith.

In the accompanying drawings:

Fig. 1 is an edge elevation of the device, embodying the invention, in use;

Fig. 2 is an edge elevation of the device, 75 the stretches of the clothes line to which it is applied being shown in section;

Fig. 3 is a detail vertical sectional view on the line 3—3 of Fig. 1 looking in the direction indicated by the arrows; 80

Fig. 4 is a similar view, the cloth holding devices being swung open so as to adapt the device to be applied to or removed from the line;

Fig. 5 is a perspective view of the device 85 with the cloth removed;

Fig. 6 is a side elevation of the device illustrating one manner in which the lower stretch of the clothes line may be engaged therewith to take up slack in the line; 90

Fig. 7 is a similar view illustrating another of the many ways in which the said lower stretch may be so engaged.

In the drawings the reference letter L indicates in general the ordinary clothes line 95 which is trained about the pulleys P and the ends of which line are tied together in a knot K as is customary. As before stated it has been heretofore impractical to clean the entire length of the line because of the 100 fact that the knot K could not pass the pulleys and therefore the upper stretch of the line has been left uncleared and in a short while accumulates considerable dust and dirt. Generally speaking, the device 105 embodying the invention embodies swingingly connected members upon which a cleaning cloth may be arranged and which members are adapted to be closed so as to adapt the cloth snugly about the clothes line, the de- 110

vice embodying means engageable by the line in a manner to connect the closed device with the lower stretch of the line and at the same time also maintain the cloth holding members of the device in closed relation, the said means being furthermore so constructed and arranged as to permit of the lower stretch of the line being engageable therewith in various ways to take up any slack in the line.

The device so far as the cloth holding members are concerned, is formed almost in its entirety from wire material and partly from sheet metal and the same comprises 15 two members, one indicated in general by the numeral 1 and the other in general by the numeral 2. The member 1 comprises a body of frame like structure which may be formed from a single length of wire or stamped 20 from a single piece of metal and which includes a top bar 3, a bottom bar 4, and vertical sides 6. The upper portions of the sides 6 are bent in opposite directions to provide portions 7 extending parallel to and beneath 25 and in a plane with the top bar 3, and the portion of the wire lying between each of the members 7 and the respective end of the top bar 3 is bent back and forth upon itself to provide an open rope receiving eye 30 8 the throat of which is indicated by the numeral 9 and is preferably slightly restricted. The bends made in the said portions of the wire to form the eyes 8 are not sharply formed but more or less gradually 35 so that the opposite sides of the throat 9 will constitute rounded noses 10 for guiding the clothes line stretch into the eyes at the time the device is applied to the clothes line whether during the day or night. For 40 a purpose to be presently explained, cross bars 11 of wire are arranged to extend between the side members 6 in parallel relation to each other and to the top and bottom bars 3 and 4, the ends of these wires being bent, 45 as at 12, about convoluted or crimped portions 13 in the said sides 6.

Also for a purpose to be presently explained the bottom bar 4 is twisted at spaced points in its length to provide substantially 50 elliptical open fingers depending from the said bottom bar in a vertical plane therewith. The member 1 further embodies a gripping means for the cleaning cloth and this means comprises a strip 15 which is 55 extended across between the upper portions of the sides 6 of the member 1 substantially at the bends forming the portions 7, and the said strip is provided with a laterally projecting flange 16 formed with a longitudinal series of gripping teeth 17.

The member 2 of the device comprises a bottom bar 18 and sides 19, and the said bottom bar is twisted at intervals in its length to provide angularly upstanding 65 fingers 20 corresponding to the fingers 14,

the said fingers 20 being inclined upwardly at an acute angle to the plane occupied by the members 18 and 19. At intermediate points in their length, the sides 19 of the member 2 are provided with inwardly offset portions 21 about which are secured the ends of a gripping strip 22 corresponding to the strip 15 and provided along its lower edge with a laterally projecting flange 23 provided with a longitudinal series of teeth 75 24. The upper portions of the sides 19 are coiled, as at 25, to hingedly fit the top bar 3 of the member 1, and beyond the coils 25 are bent to extend upwardly radial to the bar 3, as at 26, thence at right angles 80 toward each other, as at 27, and thence parallel to the portion 26, as at 28, the extremities of the portions 28 being bent about the said top bar 3, as indicated by the numeral 29. In this manner and by this means 85 the members 1 and 2 are swingingly connected and it will be evident, particularly by reference to Fig. 4, that the member 2 may be swung about the top bar 3 of the member 1 to a position to permit of the convenient 90 introduction of the stretch of a clothes line in the eyes 8 of the said member 1. It will also be observed by reference to Fig. 3 that after the line has been so engaged, the member 2 may be swung downwardly so as to 95 close the throats 9 to the eyes 8 and thus retain the clothes line in engagement in the eyes, the upper portions of the sides 19 of the member 2 extending transversely across 100 the throats of the eyes. It will also be evi- 105 dent that the portions 26, 27 and 28 constitute the elements of finger pieces rigidly connected with the member 2 and adapted to be manipulated to swing this member about the top cross bar 3 of the member. 110

The cleaning cloth employed in connection with the device is indicated by the numeral 30 and by reference to Fig. 4 of the drawings it will be observed that the cloth is applied to the members 1 and 2 by passing one end of the cloth through the space between the bar 4 of the said member 1 and lower one of the cross bars 11. The cloth is then passed about this bar 11 and through the space between this bar and the other bar 11, after which it is led upwardly past the toothed edge 17 of the gripping member 15. The cloth is then led past the toothed edge 24 of the member 22, and about the said member 22 and likewise about the top bar 3 of said member 1. The ends of the cloth are then brought together and united in any convenient manner as, for example by one or more safety pins 31. The upper stretch of the clothes line L is now laid 115 against the portion of the cloth which extends between the gripping members 15 and 22, and the said stretch of the line and the portion of the cloth engaged thereby are urged in the direction of the eyes 8 and 120 125 130

until the line has been engaged in said eyes. The member 2 is in the meanwhile swung downwardly toward the member 1, and in the final disposition of the parts as

- 5 shown in Fig. 3, the cloth will be firmly clamped by the toothed edges of the flanges of the members 16 and 22 and will be snugly drawn about the clothes line. In this manner the cloth is caused to snugly encompass
- 10 the upper stretch of the clothes line and when the device is slid along said line will of course thoroughly wipe off and clean the same. When it is desired to present a fresh or clean surface of the cloth to the line it
- 15 is only necessary to relatively open the members 1 and 2 as shown in Fig. 4 and then slide the cloth longitudinally a short distance of its length.

After the device has been engaged with

- 20 the upper stretch of the line in the manner above pointed out, the lower stretch of the line is engaged over one or more of the fingers 14 and one or more of the fingers 20, this being done either as shown in Fig. 25 1 or as shown in Fig. 6, or even for example as shown in Fig. 7, and in fact there are many ways in which the said lower stretch of the line might be engaged with any or all of the fingers 14 and 20, this engagement
- 30 of the said stretch of the line with the said fingers serving to connect the closed device with the said lower stretch so that when motion is imparted to this stretch the device will be drawn along the upper stretch
- 35 of the line at the same time the said upper stretch is drawn in the opposite direction through the device. As a natural consequence there will be a relatively rapid movement of the device and the line passing
- 40 through the eyes thereof so that the cloth will be adapted to thoroughly clean the entire length of the line. The engagement of the lower stretch of the line with the fingers 14 and 20 serves also to maintain the members 1 and 2 in flexibly closed relation so
- 45 that the cloth will be held firmly by the coacting gripping means about the line and so that there can be no disarrangement of the parts. Also the engagement of the said
- 50 lower stretch of the line in a zig-zag or crossed manner between, over, and below the said fingers provides for taking up of slack in the line to substantially any extent desired. By reference now to Fig. 1 of the
- 55 drawings it will be readily understood that whereas it has heretofore been only possible to clean one-half the length of the line, by the use of the device embodying the invention practically the entire length of the
- 60 line may be cleaned so that after the device has been used both stretches of the line will be free from dust and dirt.

Of course any suitable cleaning composition may be employed upon the cloth if

- 65 found desirable and in fact two of the de-

vices might be employed upon a line to follow one another, one supporting a wet cloth carrying a cleaning composition and the other a dry wiping cloth.

Having thus described the invention, what

is claimed as new is:

1. A cleaning device for pulley clothes lines, comprising associated members relatively movable to open and closed positions, a wiper cloth disposed between the members, the members being adapted to confine between them one stretch of the line to be cleaned and with the wiper cloth encompassing said stretch, and means whereby both of said members may be connected with the other stretch of the line.

2. A cleaning device for pulley clothes lines comprising swingingly connected members arranged to confine between them a wiper cloth and a stretch of the clothes line encompassed thereby, the said members being provided with means engageable by the other stretch of the line for connecting the closed device with the last-mentioned stretch and for maintaining the members closed.

3. A cleaning device for pulley clothes lines comprising swingingly connected members, one of said members having seating means to receive one stretch of the clothes line and a cloth encompassing the stretch, the other member when in closed position being designed to retain the said line stretch and cloth within the seat, and means associated with both of said members and engageable by the other stretch of the clothes line to connect the closed device with the last-mentioned stretch for travel therewith and maintain the second-mentioned member in closed position.

4. A cleaning device for pulley clothes lines comprising a member provided with spaced open eyes to receive a stretch of the clothes line, a second member associated with the first-mentioned member and arranged to close said eyes, means associated with the members for supporting a wiper cloth and holding the same in encompassing relation to the said line stretch, and means adapting both of said members for connection with the other stretch of the line.

5. A cleaning device for pulley clothes lines comprising swingingly connected members, a wiper cloth supported by and between the members, the members being arranged to accommodate and retain between them and within a fold of the cloth one stretch of the clothes line, means associated with the members and engageable by the other stretch of the clothes line to connect the closed device for travel with the last-mentioned stretch and to maintain the members in yieldably closed relation, and coacting gripping means for the wiper cloth carried by the said members.

6. A cleaning device for pulley clothes

- lines comprising swingingly connected members arranged to confine between them a stretch of the clothes line and a wiper cloth encompassing the said stretch, and a plurality of anchoring elements carried by each of the said members, the elements upon both members being at the same time engageable by the other stretch of the clothes line whereby to connect the closed device for travel with the last-mentioned stretch, to maintain the members closed, and to permit of slack in the line being taken up.
7. A cleaning device for pulley clothes lines comprising swingingly connected members arranged to confine between them a stretch of the said clothes line and a wiper cloth encompassing said stretch, and fingers projecting from each of the members and arranged to collectively assume a relatively staggered relation when the members are closed, the other stretch of the clothes line being adapted to be engaged above, beneath, and about said fingers whereby to connect the closed device with the stretch for travel therewith, to hold the members of the device snugly about the first-mentioned stretch of the line, and to take up slack in the line.
8. A cleaning device for pulley clothes lines comprising swingingly connected members, a wiper cloth supported by and between the members, the members being arranged to accommodate and retain between them and within a fold of the cloth one stretch of the clothes line, means associated with the members and engageable by the other stretch of the clothes line to connect

the closed device for travel with the last mentioned stretch of the line and to maintain the members in yieldably closed relation, and toothed gripping bars carried by the members and arranged to engage opposite sides of that portion of the wiping cloth which is adjacent the fold which encompasses the first mentioned stretch of the clothes line.

9. A cleaning device for pulley clothes lines comprising swingingly connected members, a wiper cloth supported by and between the members, open eyes upon the opposite ends of one of the members arranged to receive the upper stretch of the clothes line, the wiper cloth having a portion of its length adapted to be folded over the said stretch of the clothes line between the eyes, means associated with the members and engageable by the other stretch of the clothes line to connect the closed device for travel with the last-mentioned stretch and to maintain the members in yieldably closed relation, and coacting toothed cross bars carried by the members and arranged to engage opposite sides of that portion of the wiper cloth which is folded over the said upper stretch of the clothes line and thereby maintain the fold in the cloth closed.

In testimony whereof we affix our signatures.
